(57) **CLAIM**

The ornamental design for a game controller attachable to a model gun, as shown and described.

DESCRIPTION

FIG. 1 is a perspective view of a game controller attachable to a model gun according to the present invention.

FIG. 2 is a front view of the game controller of FIG. 1.

FIG. 3 is a rear view of the game controller of FIG. 1.

FIG. 4 is a left side view of the game controller of FIG. 1.

FIG. 5 is a right side view of the game controller of FIG. 1.

FIG. 6 is a top view of the game controller of FIG. 1.

FIG. 7 is a bottom view of the game controller of FIG. 1; and,

FIG. 8 is a reference view in which the game controller of FIG. 1 is attached on a model gun and the model gun is represented by broken lines.

The broken lines of FIG. 3 and illustrating the model gun are for environmental purposes only and form no part of the claimed design.
